HYPODERMIC SYRINGE

Arthur E. Smith, Los Angeles, Calif.

Application May 31, 1947, Serial No. 751,591

4 Claims. (Cl. 128—220)

1

This invention relates to improvements in disposable hypodermic syringes.

The general object of the invention is to provide an improved single-use hypodermic syringe whereby medicinal compounds such as penicillin-oil-wax may be administered in an efficient manner.

A more specific object of the invention is to provide an improved ampule stopper particularly adapted for use as an element in a disposable syringe.

A further object of the invention is to provide a novel plunger for ampule type syringes.

Another object of the invention is to provide a novel closure for the ampule of a disposable syringe.

Another object of the invention is to provide a disposable syringe including a front ampule closure having novel finger engaging means thereon.

Other objects and advantages of the invention will be apparent from the following description taken in connection with the accompanying drawings, wherein

Fig. 1 is a central sectional view of a disposable syringe showing my invention;

Fig. 2 is a view similar to Fig. 1, showing the syringe prepared for use;

Fig. 3 is a view similar to Fig. 1, showing the syringe after the contents have been discharged;

Fig. 4 is a view similar to Fig. 1, showing a modification of my invention;

Fig. 5 is a fragmentary sectional view showing the manner in which the needle is moved to active position, and

Fig. 6 is a fragmentary central sectional view showing a modified form of needle construction.

Referring to the drawing by reference characters, I show my invention as embodied in a disposable syringe which is indicated generally at 10. As shown, the syringe includes an ampule 11, a plunger 12, a front member 13 and a stopper 14. The ampule and plunger may be made of glass or plastic material, while the front member 13, the stopper 14 and the piston 15 on the plunger 12 may be made of natural or synthetic rubber.

The ampule 11 is in the form of a cylinder and the plunger 12 is also cylindrical and includes a reduced portion 16 from which a stem 17 extends. The stem 17 has a head 18 thereon. The piston 15 has a recess 19 in one end thereof which communicates with an enlarged recess 20. The recesses 19 and 20 are of a size to receive and grip the portions 17 and 18 on the plunger and the end 21 of the piston is plane and engages

2

the plane face 22 on the reduced portion 16 of the plunger. The forward end of the piston includes a recess 23 which receives the tip of a hypodermic needle (to be later described) when the plunger is at the extreme inward limit of its movement.

The front and back peripheries 24 and 25 of the piston 15 are rounded so that dragging and binding are reduced to a minimum when the piston moves forward in injecting the material and when the piston moves rearwardly in testing as will be later described. The piston also includes peripheral grooves 26 which prevent dragging and binding.

15 The stopper 14 includes a peripheral flange 30 which engages the end of the ampule 11. The outside diameter of the flange 30 is substantially the same as the outside diameter of the ampule 11. The forward end of the stopper 14 has a recess 31 while the rear end of the stopper has a reduced recess 32. The recesses 31 and 32 are coaxial and recess 32 is preferably smaller than recess 31. The recesses 31 and 32 are connected by a thin diaphragm 33 which is adapted to be pierced by a hypodermic needle prior to injection.

20 The front member 13 is in the nature of a resilient cap and includes a peripheral bead or flange 35 which is adapted to be engaged between the index and second finger of the operator while the injection is being made. The front member includes a forwardly projecting tip 36 which has a curved recess 37 in its forward face. The front member includes a rearwardly projecting tip 38 which is normally slightly larger than the recess 31 in which it fits to form a seal. The front member includes a bore 39 which is coaxial with the front member and ampule and in this bore I seat one end portion of a hypodermic needle 40 which extends through the bore and pierces the tip 38 and enters the recess 31 but normally does not pierce the diaphragm 33.

25 The needle includes a bulbous shoulder portion 41 which fits in the recess 37 in the tip 36 when the needle is fully seated. The needle projects forwardly at 42 beyond the bulbous portion. The outer end 43 of the needle and the inner end 44 thereof are both sharpened as shown. An elongated cap member 45, preferably made of pliable plastic, surrounds the needle and engages the tip 36 tightly in the position shown in Fig. 1. The tip 36 preferably tapers towards the ball 44 so that a tight fit may be had at the cap 45.

30 The head 18 on the plunger stem is disposed near the center of the piston 15 and thus in pushing and in pulling the piston there is a sufficient

amount of rubber in shear to provide a smooth action. Further, the space 48 between the end 47 of the body of the plunger and the adjacent end 21 of the piston allows the rubber on the piston to move into this space and thus a binding action is avoided. The construction of the piston in a syringe of the present nature is important as the movement of the piston must be under accurate control and if there is any binding a jar occurs when the parts release and this is a serious objection. I have overcome the objections mentioned by the particular manner in which the piston and plunger are made so that a smooth movement is secured throughout the injection.

In use, with the parts in the position shown in Fig. 1, the operator removes the flexible cap 45 and then by squeezing the cap (as shown in Fig. 5) engages the bulb 41 and pushes the needle point 44 through the diaphragm 33 so that the parts assume the position shown in Fig. 2, in which condition the needle communicates with the interior of the ampule. Pressure on the outer end of the plunger 12 then causes the contents of the ampule, such as penicillin-oil-wax, to be injected through the needle.

In using many drugs it is essential that injection be not made in a vein or artery and to determine whether the needle has been inserted in a vein or artery, after the insertion is made, the plunger is pushed slightly inwardly and then withdrawn and if the point of the needle has punctured a blood vessel it will cause blood to be aspirated into the ampule. Thus a check is provided against improper injection.

In Figs. 4 and 5 I show a modification of my invention. In the modification the ampule 11' and the piston 15' are similar to those previously described. The front member 50 includes an integral stopper portion 51. The front member has a skirt 52 which engages the exterior of the ampule 11'. The front member includes a shoulder 53 which like the flange 35 may be engaged by the fingers of the operator while the injection is being made. The front member includes a projecting tip 54 which is tapered and is provided with a cylindrical bore 55 which extends therethrough and extends part way through the cork portion 51 and terminates short of a diaphragm 56. The cork portion includes a recess 57. A flexible cap 45' surrounds the needle 42'.

In use the cap 45' is removed and squeezed to the position shown in Fig. 5 so that it engages the shoulder portion 41' on the needle so that the needle may be pushed inwardly through the diaphragm 56 to the position shown in Fig. 5 to place the needle in communication with the interior of the ampule. The plunger 12' and associated parts in the modification function the same as heretofore described.

In both types of my syringes the bores 39 and 55 are of a size to permit the needle to slide freely therein without wobbling and thus the needle is supported.

In Fig. 6 I show a modification wherein the ampule 11'' has a front member 13'' and a stopper 14'' similar to that previously described. In the modification the end of the tip of the front member is plane as at 60, while the needle 42'' has a generally cone-shaped protuberance 41'' thereon. The protuberance 41'' has a plane rear face 61 which engages the plane face 60 of the front member when the needle is moved to injecting position.

From the foregoing description it will be apparent that I have invented a novel disposable hypo-

dermic syringe which is efficient, which is safe in use and which can be economically manufactured.

Having thus described my invention, I claim:

5 1. A disposable syringe including an ampule having a plunger slidable thereon, a piston on said plunger, a stopper in said ampule remote from said piston, said stopper having an outwardly opening recess therein and having an interiorly opening recess coaxial with the outwardly opening recess, a diaphragm separating said recesses, a front member on said ampule, said front member having a finger engaging shoulder thereon, said front member having an inwardly directed tip thereon disposed in said outwardly opening recess of said stopper, said front member having a forwardly projecting tip thereon, said front member having a bore extending through said forward tip and terminating short of the inner end of said inwardly extending tip, a needle slidably in said bore and having its inner end extending through and projecting beyond said inwardly extending tip, said needle having a protuberance spaced from said tip, and a flexible cap about the outer end of said needle and seated on the forwardly projecting tip on said front member.

2. A disposable syringe including an ampule having a plunger slidable therein, said plunger comprising a cylindrical body having a forwardly extending reduced portion, a piston having a recess receiving said reduced portion, a stopper in said ampule remote from said piston, said stopper having an axial recess and having a diaphragm closing said stopper recess, a front member on said ampule, said front member having a finger engaging shoulder thereon, said front member having a forwardly and a rearwardly projecting tip thereon, said front member having a bore extending through said forward tip and terminating short of the inner end thereof, a needle slidably in said bore and having its inner end extending through said rearward tip, said needle having a protuberance spaced from said forward tip, and a flexible cap about the outer end of said needle and seated on the forwardly projecting tip on said front member.

3. A disposable syringe including an ampule having a plunger slidable therein, said plunger comprising a cylindrical body having a forwardly extending reduced portion, a reduced stem on said reduced portion, a head on said stem, a piston having a recess receiving said stem and head, a stopper in said ampule remote from said piston, said stopper having an outwardly opening recess therein and having an interiorly opening recess coaxial with the outwardly opening recess, a diaphragm separating said recesses, a front member on said ampule, said front member having a finger engaging shoulder thereon, said front member having an inwardly directed tip thereon disposed in said outwardly opening recess of said stopper, said front member having a forwardly projecting tip thereon, said front member having a bore extending through said forward tip and terminating short of the inner end of said inwardly extending tip, a needle slidably in said bore and having its inner end extending through and projecting beyond said inwardly extending tip, said needle having a protuberance spaced from said tip, and a cap seated on the forwardly projecting tip on said front member.

4. A disposable syringe including an ampule having a plunger slidable therein, said plunger comprising a cylindrical body having a forwardly

extending reduced portion, a reduced stem on said reduced portion, a head on said stem, a piston having a recess receiving said stem and head, said piston having a planar rear end and said plunger reduced portion having a planar end face engaging said piston rear end, the rear end of said piston being spaced from the end of the body of the plunger, said piston having a rounded periphery at its front and rear ends, a stopper in said ampule remote from said piston, said stopper having an outwardly opening recess therein and having an interiorly opening recess coaxial with the outwardly opening recess, a diaphragm separating said last mentioned recesses, said stopper having a peripheral flange thereon engaging the end of said ampule, a front member on said ampule, said front member having an outwardly extending, peripheral, finger engaging flange thereon, said front member having an inwardly directed tip thereon disposed in said outwardly opening recess of said stopper, said front member having a tapering forwardly projecting tip thereon, said front member having a bore extending through said forward tip and terminating short of the inner end of said inwardly extending tip, a needle slidable in said bore and having its inner end sharpened and extending

5 through and projecting beyond said inwardly extending tip, said needle having a bulbous portion spaced from said tip, the forward end of said outwardly directed tip having a recess adapted to receive said bulbous portion, and a flexible cap about the outer end of said needle and seated on the forwardly projecting tip on said front member.
